United States Patent Office

Des. 184,191
Patented Dec. 30, 1958

184,191

ADJUSTABLE SNAP

William M. Noe, South Pasadena, Calif., assignor to B-N Corporation, doing business as Auto-Crat Manufacturing Co., Los Angeles, Calif., a corporation of California

Application January 20, 1958, Serial No. 49,317

Term of patent 14 years

(Cl. D17—1)

Fig. 1 is a perspective view of an adjustable snap showing my new design.

Fig. 2 is an edge view as seen from the opposite side of Fig. 1.

The characteristic features of my design reside in the portions shown in full lines in the drawings.

I claim:

The ornamental design for an adjustable snap, substantially as shown.
